UNITED STATES PATENT OFFICE.

PARKER B. HASKELL, OF LYNN, MASSACHUSETTS, ASSIGNOR, BY DIRECT AND MESNE ASSIGNMENTS, OF ONE-THIRD TO WALTER B. POHLE, OF LYNN, MASSACHUSETTS, AND ONE-THIRD TO SUSAN V. RUSSELL, OF CHELSEA, MASSACHUSETTS.

CRANK CASING FOR INTERNAL-COMBUSTION ENGINES.

Application filed August 18, 1924. Serial No. 732,741.

To all whom it may concern:

Be it known that I, PARKER B. HASKELL, a citizen of the United States of America, and a resident of Lynn, in the county of Essex and State of Massachusetts, have invented certain new and useful Improvements in Crank Casings for Internal-Combustion Engines, of which the following is a specification.

10 This invention relates to crank casings for internal combustion engines and has for its object the provision of means whereby the oil in the crank troughs may be quickly changed and the sediment therein removed.

15 These objects are attained by the mechanism illustrated in the accompanying drawing.

For the purpose of illustrating the invention, one preferred form thereof is shown in the drawings, this form having been found to give satisfactory and reliable results, though it is to be understood that the various instrumentalities of which the invention consists can be variously arranged and organized and that the invention is not limited to the precise arrangement and organization of the instrumentalities as herein shown and described, except as required by the scope of the appended claims.

20 Of the drawings:

Fig. 1 represents a plan of a crank casing embodying the principles of the present invention.

Fig. 2 represents a side elevation of the same with one of the oil troughs removed.

Fig. 3 represents a vertical transverse section on line 3, 3 on Figs. 1 and 2.

Fig. 4 represents a horizontal section of one of the removable oil troughs, on line 4, 4 on Figs. 3 and 5, and

Fig. 5 represents a vertical transverse section of the oil troughs on line 5, 5 on Fig. 4.

Similar characters indicate like parts throughout the several figures of the drawing.

In the drawings, 10 is a crank casing preferably provided with a bonnet, which, as it forms no part of the present invention, is not shown in the drawings.

50 The casing 10, as illustrated in the drawings, is adapted to contain four cranks 11 of an internal combustion engine, one of said cranks 11 being shown in Fig. 3 of

the drawings as secured to a crank shaft 12 and having the usual connecting rod 13 pivotally connected to its free end.

Beneath each crank 11 is disposed an oil trough 14 adapted to be partly filled with oil through which the free end of crank 11 must pass as the crank shaft 12 revolves, thereby thoroughly lubricating the bearings between the crank 11 and the connecting rod 13.

It is usual to provide crank casings with such oil troughs or pans 14 but these pans 65 or troughs 14 are liable to have sediment collect therein which is very objectionable.

Consequently, the troughs or pans 14 must be cleaned out from time to time and the old oil replaced by a fresh supply of 70 oil.

To do this, it is ordinarily necessary to take the crank casing 10 apart in order to gain access to the oil troughs 14.

This takes considerable time and requires 75 the services of expert labor.

It is particularly objectionable when the crank case is a part of the installation of a fire truck or some other emergency vehicle which is liable to be suddenly called into 80 service.

For instance, in some motor vehicles, it takes several hours to disconnect the crank case, take out the oil pans, remove the sediment and oil from said pans, fill them again 85 and then assemble the crank casing.

Should an alarm be sounded when this operation is being performed, this particular apparatus could not respond to the call until the work was completed.

This is manifestly a great objection and the present invention is made to overcome this difficulty and make it possible to accomplish the work piecemeal with a minimum amount of labor and in a very short 95 time.

This desired result is accomplished by the following means:

One side wall of the casing 10 has a number of openings therein, preferably one for 100 each crank 11, and through these openings 15 are inserted the troughs 14 so that there will be one under each crank.

The inner end of each trough 14 has a depression or recess 16 in its wall into which 165 extends a projection or lug 17 preferably

formed upon the inner face of the rear wall of said casing 10.

The inner end of the trough or pan 14 is properly positioned by said lug 17 in the recess 16 and all vertical or lateral movement of said inner end is effectually prevented.

The outer end of each trough 14 is provided with a flange 18 adapted to bear 10 against a flat face on the front wall of the casing 10 and be secured thereto by bolts 19 passing therethrough into the front wall of the casing 10.

Each trough 14 has a depression 20 in the 15 bottom thereof in which the sediment is adapted to collect.

When it is desired to replace the oil in a trough or pan 14 the securing bolts 19 may be removed, and the pan 14 taken out 20 of the casing 10 through its opening 15.

The sediment and oil therein may be quickly removed from the pan, which may then be refilled and returned to its original position, all without disturbing the casing 25 10 itself, or the other troughs 14.

In other words, one trough 14 may be removed at a time and if an alarm is sent in, all that it is necessary to do is to immediately replace the trough 14 in the casing 10 30 and secure it in position.

The fire truck will then be ready for immediate use. The other troughs 14 may be successively removed, each preferably being replaced before another is disconnected 35 from the casing.

Obviously this is of great advantage.

It is sometimes desirable to remove the sediment from the troughs at more frequent intervals than it is necessary to refill the 40 troughs with a new supply of oil and therefore provision is made whereby this may be accomplished.

The means employed to obtain this result is as follows:

45 Each depression 20 has a valve member 21 therein, said member being cylindrical with an elongated slot 22 extending diametrically therethrough.

Ordinarily, the slot 22 is vertical so that 50 the sediment in the trough 14 may settle in this slot.

On either side of the valve 21 are passages 23, 24 connected to the depression 20 by ports 25, these ports being alined and 55 adapted to register with the opposite ends of the slot 22 when the said slot has been moved into a horizontal position.

The outer ends of the passages 23, 24 are 60 under normal conditions closed by plugs 26 threaded thereto.

The valve 21 is adapted to be rotated by the head 27 on the front end thereof.

When it is desired to remove the sediment 65 without removing the troughs 14, the plugs 26 are removed and air is blown through

the passage 23 into the slot 22, the valve member 21 having been rotated sufficiently to aline it with the ports 25.

This injecting of air under sufficient pressure will force the sediment in the slot 22 70 into the passage 24 from the outer end of which it will be discharged into any suitable receptacle provided to receive said sediment.

When this sediment has all been removed, 75 the valve 21 is again turned to cause the slot 22 to assume a vertical position and the plugs 26 are returned to their places.

It will be noted that while the sediment is being blown out, the valve 21 is in such 80 position that none of the air will be admitted to the interior of the trough itself.

By means of this invention the oil troughs 14 may be quickly removed separately from the casing and refilled with a fresh supply 85 of oil after the sediment has been removed from said troughs, or if the oil in the troughs is still in fairly good condition except for the sediment which has collected in the depression 20 in the bottom of the 90 trough, this sediment may be readily removed without disconnecting the oil troughs from the casing 10.

The operation and many advantages of the invention will be apparent without further description.

Having thus described my invention, I claim:

1. A crank casing having an opening in one wall thereof; and a removable oil containing splash trough having a length to extend across the said casing and adapted to be inserted through said opening and secured to said wall.

2. A crank casing having an opening in one wall thereof; a removable oil containing splash trough having a length to extend across the said casing and adapted to be inserted through said opening; a flange formed upon the outer end of said trough; 110 and means for securing said flange to the outer face of said wall.

3. A crank casing having an opening in one wall thereof; a removable oil containing splash trough having a length to extend across the said casing and adapted to be inserted through said opening; means for securing said trough to said wall; and means for supporting the inner end of said trough.

4. A crank casing having an opening in one wall thereof; a removable oil trough adapted to be inserted through said opening and having a depression in its inner end; a projection on the inner face of said casing adapted to enter said depression; and means for securing the outer end of said trough to the outer face of said wall.

5. A crank casing having an opening in one wall thereof; a removable oil trough

adapted to be inserted through said opening and provided with a sediment-collecting depression in the bottom thereof; and means for securing the outer end of said trough to the outer face of said wall.

6. A crank casing having an opening in one wall thereof; a removable oil trough adapted to be inserted through said opening and having a cylindrical chamber in the bottom thereof in which sediment is adapted to collect; a valve in said chamber adapted to close the passage from said chamber to said trough; and means for securing the outer end of said trough to said wall.

15 7. A crank casing having an opening in one wall thereof; a removable oil trough adapted to be inserted through said opening and having a cylindrical sediment-collecting chamber communicating therewith by an elongated passage; an oscillating tubular valve in said chamber having oppositely disposed slots therein, one of which is adapted to normally register with said passage; air passages on opposite sides of said chamber and communicating therewith; and means for oscillating said valve.

8. A crank casing having an opening in one wall thereof; a removable oil trough adapted to be inserted through said opening and provided with a sediment-collecting depression in the bottom thereof; means securing said trough to said casing; and means whereby the sediment may be removed from said depression without removal of said trough.

40 9. A crank casing provided with a plurality of oil containing splash troughs each having a length to extend across said casing and adapted to be removed separately from said casing through openings in a side wall thereof, one of said troughs being positioned beneath each crank in said casing.

45 10. A crank casing provided with a plurality of oil troughs adapted to be removed separately from said casing through openings in a side wall thereof, each trough be-

ing provided with means for removing the sediment from the trough without the removal of said trough from said casing.

11. A crank casing provided with a plurality of oil troughs and means for removing the sediment separately from each trough through a wall of said casing without displacing said trough.

12. A crank casing provided with an oil trough positioned in said casing and having a sediment collecting chamber in the bottom thereof; air passages communicating by ports with the opposite sides of said chamber; and a tubular valve in said chamber adapted to be oscillated to close the passage to said trough and open the ports to said air passages.

13. A crank casing having an opening in the wall thereof, said opening being rectangular at its upper end; a removable oil containing trough fitting said opening and extending therethrough into said casing, said trough having a flange on its outer end; and means for securing said flange to the outer face of said wall.

14. A crank casing having an opening in the wall thereof, said opening being rectangular at its upper end; a removable oil containing trough fitting said opening and extending therethrough into said casing, said trough having a flange on its outer end provided with holes therethrough; and bolts extending through said holes into said wall for securing said flange to the outer face of said wall.

15. A crank casing having an opening in one wall thereof; an oil containing trough adapted to be inserted through said opening with the outer end of its body portion non-revolubly positioned in said opening; and means for securing said trough to said wall.

Signed by me at 746 Old South Bldg., Boston, Mass., this 14th day of August, 1924.

PARKER B. HASKELL.
